UNITED STATES PATENT OFFICE.

THOMAS E. GRIFFITH AND LEE L. DODDS, OF CLEVELAND, OHIO, ASSIGNORS TO THE
W. S. TYLER COMPANY, OF CLEVELAND, OHIO, A CORPORATION OF OHIO.

OPERATING MECHANISM FOR ELEVATOR DOORS.

Application filed June 16, 1923. Serial No. 645,832.

To all whom it may concern:

Be it known that we, THOMAS E. GRIFFITH and LEE L. DODDS, both citizens of the United States, and residents of Cleveland, county of Cuyahoga, and State of Ohio, have jointly invented a new and useful Improvement in Operating Mechanism for Elevator Doors, of which the following is a specification, the principle of the invention 10 being herein explained and the best mode in which we have contemplated applying that principle, so as to distinguish it from other inventions.

The present invention, relating, as indicated, to operating mechanisms for elevator doors, is directed more particularly to an improved mechanism for operating the doors of an elevator enclosure, which mechanism is provided with means for preventing the 15 unauthorized opening of the doors where they, by carelessness or accident, have been left in a partially opened position. To the accomplishment of the foregoing and related ends, said invention, then, consists of 20 the means hereinafter fully described and 25 particularly pointed out in the claims.

The annexed drawing and the following description set forth in detail certain mechanism embodying the invention, such 30 mechanism constituting, however, but one of various mechanical forms in which the principle of the invention may be used.

In said annexed drawings:—

Fig. 1 is a front elevation of an elevator 35 enclosure and door embodying therein one form of our novel operating mechanism;

Fig. 2 is an enlarged elevation of the operating mechanism;

Fig. 3 is a cross sectional view on line 40 3—3, Fig. 2;

Fig. 4 is a view similar to Fig. 1, but showing a modified form of operating mechanism;

Fig. 5 is an enlarged elevation of the operating mechanism illustrated in Fig. 4;

Fig. 6 is a view partially in elevation as taken on line 6—6, Fig. 7; and

Fig. 7 is a cross sectional view on the line 7—7 in Fig. 5.

With reference to Figs. 1 to 3 inclusive, there is illustrated an elevator enclosure 1 having an opening 2 which is normally closed by a door or doors 3. The door is mounted to move laterally by means of a

hanger 4 attached to the top of the door, 55 the hanger being provided with suitable flanged wheels 5 which ride on a track 6, secured to the enclosure frame above the door. In the present form, the door is moved manually by an operator gripping 60 a suitable handle or the like and then pulling said door in the opening direction. It is usual in such types of elevator doors to employ the handle to free or unlatch the latching mechanism at the time the handle 65 is first gripped. To accomplish this, the handle, designated by numeral 7, is pivotally mounted about a pin 8 on the door 3 and a spring 9 is used to keep the handle normally pressed outwardly. A cover or 70 casing 10 may be used to confine the spring and handle, an opening being provided in one side thereof, through which the operator may grip the handle. Mounted vertically above the handle and extending through the 75 casing 10 is a vertical rod 11, which is utilized to control the latching mechanism. The lower end of this rod is engaged by a cam surface 12 formed eccentrically about the pin 8 on the handle 7, it being obvious 80 that movement of the handle will cause the rod 11 to be either raised or lowered, which action will effect the latching or unlatching of the latching mechanism to be presently described. Thus far the above description 85 relates to an ordinary construction of elevator enclosure doors and the handle operating mechanism therefor.

In the operation of elevators the operator occasionally only partly closes the doors, 90 or the door closer (not shown) for some reason fails to completely close them and they stand in a partially open position. It is essential that means be provided to prevent a further opening of the doors by someone in 95 the corridor, when the doors are standing in such partially opened position. As soon as they are closed, the doors cannot, of course, be opened from the corridor side, so that if means are provided which prevent the opening of the doors from the corridor, even though they are in a partially open position, such means are effective to prevent a complete opening of the doors from the corridor and to prevent accidents. The means which we employ for this purpose consist of the following mechanism. The upper end of rod 11 is slidably 100 105

received in a bracket or boss 13 and in such upper end is mounted a pin 14 extending through a slot 15 in the boss 13 toward the enclosure and terminating contiguous to the track 6. Pivoted about the pin 14 is a cam plate 16 having an eccentric cam 17 formed on its upper edge and having a weighted lower portion 18 which keeps the cam plate by gravity normally in latching position, as will be presently described. Mounted on the enclosure, in this embodiment of our invention on the track 6, is a longitudinally extending plate 20, said plate being located immediately above the cam plate 16. As seen in Fig. 2, the cam 17 of plate 16 normally engages the plate 20 on account of the normally raised position of rod 11, which engagement results in latching or holding the door from lateral movement to the left or opening direction. It will be obvious that, if the door and cam plate 16 are moved toward the left, the eccentric cam 17 will, on account of its relative arrangement, become tightly engaged against the plate 20 and the door prevented from movement in such direction.

In operation the operator grips the handle 7 to pull the elevator door open and by such gripping action rotates the handle and cam 12 about the pin 8, thus dropping the vertical rod 11. When the rod 11 is dropped, it lowers the cam plate 16 out of engagement with the plate 20 and the door may be moved to the left to open position. If the door is now returned to closed position, the handle is released and the spring 9 actuates to raise the rod 11 and cam plate 16. The plate 20 may be extended the full length of the travel of cam 17, or, as shown, may extend for a short distance adjacent the closed position of the door. In use of elevators the operator always pushes the door nearly shut before starting his car, and in some instances, the door does not completely close, and it is in such cases that the present novel operating mechanism operates to prevent the opening of such door from the corridor side. In the closing movement of the door, after the handle 7 has been released and the rod 11 and cam plate 16 raised, the cam 17 rolls along the underside of plate 20, but does not interfere with the closing movement of the door.

The present operating means do not in any way affect the normal operation of the elevator doors and they add but few parts to the ordinary operating mechanism. It will be evident, however, that the action of cam 17 and plate 20 effectively prevents the opening of the doors from the corridor side, should such doors be left in partially opened position.

A similar construction is shown in Figs. 4 to 7 inclusive, in which, however, a chain device is employed in place of the handle member 7 for operating the latching mecha-

nism and for pulling open the door. 25 denotes the elevator enclosure, 26 the door, and 27 the hanger therefor, on which are mounted wheels 28 adapted to guide and support the door on a track 29 secured to the enclosure frame. Mounted about a pin 30 in a casing 31, secured to the top of the door 26, is a cam plate 32. The plate 32 is provided on its upper side with an eccentric cam surface 33, similar to the cam 12, and the lower end is formed with a weight 34 which keeps the cam 33 normally in raised position. Attached to the plate 32 at one side thereof is a chain or other flexible element 35, which extends downwardly through the casing 31 along the door within convenient reach of an operator, the lower end of the chain being slidably received in a perforated bracket 36 and having thereon a ring or enlarged loop 37. In use the operator may grip either the ring 37 to rock the plate 32 about its pivot, or may take hold of the chain above the bracket 36, which action also tends to pull the chain downwardly. Mounted on the hanger 27 is a bracket 40, in which is slidably carried a vertical rod 41. Rod 41 extends downwardly through the top of casing 31 and is engaged by cam 33. Carried by and extending from the rear side of said rod is a pin 42, similar in construction to the pin 14, said pin extending through a slot 43 in the boss 40 and in the hanger 27 toward the track 29. Pivots mounted on said pin is a cam plate 44 adapted to engage a longitudinal plate 45 fixed to the track 29 above the member 44. The operation of the latching mechanism which comprises the rod 41, the cam plate 44 and the plate 45 is identical with the operation of rod 11, cam plate 16 and plate 20, hereinbefore described. The mechanism set forth in the last named embodiment of the invention is particularly advantageous in use on very high elevator doors, where, if a rod similar to rod 11 were used, considerable warping might develop and throw the latching mechanism out of adjustment. By using a comparatively short rod, as 41, and controlling the movement thereof by a chain, we eliminate any possibility of the parts becoming misaligned.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

1. In an elevator enclosure, the combination of a slidably mounted door, an operating handle therefor, a plate mounted on said enclosure, a pivotally mounted cam plate adapted to frictionally cooperate with said first named plate to prevent movement of

said door in one direction, and means actuated from said handle for rendering said cam plate inoperative.

2. In an elevator enclosure, the combination of a slidably mounted door, a laterally extending plate mounted on said enclosure, a vertical rod slidably mounted on said door, means for raising and lowering said rod, a cam plate pivotally mounted on said rod and adapted to frictionally engage said first-named plate when the rod is in raised position to prevent lateral movement of the door in one direction.

3. Door locking mechanism comprising a fixed laterally extending plate, a vertical rod carried by the door, a cam plate pivotally mounted on said rod, an eccentric cam surface on said cam plate adapted to frictionally engage said first named plate to prevent

lateral movement of the door in one direction, and means for raising and lowering said rod to engage or disengage said cam plate with said first named plate.

4. In an elevator enclosure having an opening therein, the combination of a slidably mounted door adapted to close said opening, a laterally extending plate mounted on said enclosure adjacent the closed position of said door, a vertical rod slidably mounted on the door, a handle member for raising and lowering said rod, and a cam plate pivotally mounted on said rod, said cam plate being adapted to frictionally engage said first named plate to prevent lateral movement of the door in one direction.

Signed by us this 8th day of June, 1923.

THOMAS E. GRIFFITH.

LEE L. DODDS.
